CURTAIN STRETCHER

Kenneth J. Unwin, Kenosha, Wis., assignor, by
mesne assignments, to Quaker Stretcher Com-
pany, Kenosha, Wis., a corporation of Wis-
consin

Application November 22, 1946, Serial No. 711,739

3 Claims. (Cl. 45—24)

1

This invention relates to curtain stretchers of the "zipper" type wherein a shuttle or like member adapted to slide along the rails of a stretcher causes the edges of the curtain to be caught by the fastening devices that are mounted on these rails.

A general object of the invention is to simplify the manufacture and reduce the cost of the stretchers while retaining the advantages of prior construction thereof.

A further object is to provide an improved curtain stretcher of the aforesaid type in which the curtain fastening devices have hooked ends for holding the curtain against the rail, and wherein a longitudinal groove is formed in the rail to accommodate the hooked ends of the fastening devices.

A still further object is to enable the fastening devices to be mounted on a curtain stretcher rail merely by clamping them between separable portions of the rail.

Still another object is to provide an improved adjustable end bar and holding means therefor, such holding means comprising a pair of clamps respectively adapted to embrace the top and bottom rails of the stretcher and having lugs which cooperate with portions of the end bar to retain the bar firmly in its position of use.

Various other objects, advantages and features of the invention will be apparent from the following specification when taken in connection with the accompanying drawings wherein a certain preferred embodiment is set forth for purposes of illustration.

In the drawings, wherein like reference numerals refer to like parts throughout:

Fig. 1 shows, in elevation, a curtain stretcher of the type in which my present invention may be utilized to advantage;

Fig. 2 is a perspective view of the adjustable end bar and associated holding means, portions of the top and bottom rails of the stretcher being indicated in phantom;

Fig. 3 is a vertical sectional view taken on the line 3—3 in Fig. 2;

Fig. 4 is a fragmentary perspective view of a rail and the curtain fastening devices mounted thereon;

Fig. 5 is a perspective detail view of a curtain fastening device;

Fig. 6 is a cross section taken on the line 6—6 in Fig. 4;

Fig. 7 is a longitudinal section along the line 7—7 in Fig. 4, also showing the shuttle in its position of use;

2

Fig. 8 is a sectional view taken on the line 8—8 in Fig. 7; and

Fig. 9 is a perspective view of the shuttle.

Referring particularly to Fig. 1, the stretcher comprises top and bottom rails 10 and 11 and end rails 12 and 13, respectively. Legs 14 hinged respectively to the end rails 12 and 13 support the stretcher in the position shown. The top rail 10 and bottom rail 11 are attached at their ends to the rails 12 and 13 by clamps 15 and 16 or in any other suitable manner. The rails 10 and 11 are hinged at their midportions, as indicated at 18 and 20, so that the rails 10 and 11 may be bent slightly toward each other when a curtain is being attached to the frame and then straightened to stretch the curtain taut. A slotted spreader bar 22 depending from the rail 10 is attached to the rail 11 by a thumb screw 24 which is tightened to hold the rails 10 and 11 in their straightened positions. An adjustable end bar 26, constituting one of the features of the invention, is adapted to be inserted in a hem of the curtain and is disposed substantially in vertical position between the top and bottom rails 10 and 11. The other three edges of the curtain are attached to the rails 10, 11 and 12 in a manner which will be explained presently, and the location of the bar 26 is adjusted horizontally in accordance with the length of the curtain.

Referring now to Figs. 2 and 3, it will be seen that the upper end of the bar 26 has a blunt point 28 to facilitate insertion of this bar in the hem of the curtain. For holding the bar 26 in its adjusted position there are provided a clamp 30 on the top rail 10 and a clamp 32 on the bottom rail 11. The clamp 30 includes plates or jaws 34 and 36 which partially embrace the upper rail 10. A shouldered tongue 38 bent out from the plate 34 is received in an aperture in the plate 36 and serves as a fulcrum on which the plates 34 and 36 pivot. A wing nut 40 and bolt 42 enable the plates 34 and 36 to be squeezed together against the upper and lower edges of the rail 10. A horizontally extending tongue 44 of the plate 34 is inserted in a suitable opening near the upper end of the bar 26. Lugs 46 and 48 extend down from the front end of the plate 34 overhang the upper edge of the rail 10 on either side of the bar 26. A lug 50 bent up from the forward edge of the plate 36 is adapted to grip the front face of the rail 10 on one side of the bar 26.

The lower clamp 32 comprises two plates or jaws 52 and 54 which partially embrace the lower

rail 11. A shouldered tongue 56 bent out from the plate 54 is received in an aperture in the plate 52 and serves as a fulcrum on which the plates 52 and 54 pivot. A wing nut 58 and bolt 60 are provided to draw the plates 52 and 54 together and thereby grip the rail 11. Forwardly projecting fingers 62 and 64, offset downwardly from the upper edge of the plate 32, are disposed on either side of the vertical bar 26 and are slightly hooked at their outer ends to hold the bar 26 against the front face of rail 11. A lug 66 bent up from the front edge of the plate 54 is adapted to grip the front face of the rail 11 on one side of the bar 26.

The rails 10, 11 and 12 are provided respectively with rows of fastening devices 68, Figs. 4 and 5, having hooked portions 70 that are adapted to catch the edge portions of a curtain C as shown in Fig. 6. It is not necessary to provide the rail 13 with fastening devices as 68, because of the manner in which the curtain is attached to the stretcher with its hem held by the bar 26, although there may be instances in which it would be desirable to provide the rail 13 with these fastening devices.

Each fastening device 68 is formed preferably as illustrated in Fig. 5. As there shown, a suitable length of resilient wire is bent into a U-shape at its midportion as indicated at 72. At the ends of the U the wire is looped several times to form coil springs 74. The ends of the wire then are extended from the coils 74 and are formed to provide the hooks 70 having pointed ends 71.

The bight 72 of each fastening device 68 is placed between two longitudinally extending separable portions of a rail such as the rail 10, Figs. 4 and 6. These separable portions consist of a rail member 76 and a strip 78 secured thereto by suitable fastening means such as the screws 80. Preferably each screw 80 is so located that it serves to anchor a fastening device 68 by passing through the bight 72 thereof. The bight 72 is held between the strip 78 and a rib 82 on the adjacent edge of the member 76. The coils 74 of the fastening device 68 are seated in a rabbet 84 defined in the forward face of the member 26 adjacent the rib 82. A lip 86 along the forward edge of the strip 78 over-hangs the coils 74 to maintain them firmly seated in the rabbet 84. Another lip 88 along the rear edge of the strip 78 interlocks with the rib 82 on the member 76. The hooks 70 normally lie against an oblique surface 90 on the forward face of the member 76.

In accordance with the invention, the pointed ends 71 of the hooks 70 are received in a groove 92, Figs. 4 and 6, which is provided in the forward face of the member 76 extending longitudinally thereof. The elastic force of the coiled springs 74 normally serves to maintain the hook ends 71 in the groove 92. In order to fasten an edge of the curtain C to the stretcher rail as 10, each hook 70 is moved outwardly against the action of its spring 74, and the edge portion of the curtain C is disposed between such hook 70 and the member 76 so as to cover the groove 92 as shown in Fig. 8. The hooks 70 then are released so that the springs 74 restore these hooks, thereby causing the points 71 to penetrate the curtain material and pass into the groove 92 as shown in Fig. 6, whereby the curtain C is pinned to the rail.

The shuttle 94, Figs. 7, 8 and 9, which constitutes a further feature of this invention, is employed by the user of the curtain stretcher to effect retraction of the hooks 70 from the member 76 and return of the hooks 70 into curtain

gripping position. The shuttle is shaped so that it may be conveniently grasped by hand and moved along the rail. A cam plate 96 of metal or other suitable material carried by the shuttle 5 is adapted to slide along a groove 98 formed in the oblique face 90 of the rail member 76 in back of the hooks 70. A shoe 100 extending from the shuttle 94 is pressed against the curtain C adjacent the groove 92, which thus is disposed between the shoe 100 and the cam plate 96. As the cam plate 96 is moved along the groove 98, the hooks 70 successively ride on the cam surface of plate 96, being moved to a maximum extent away from the rail member 76 and then being re-turned as the cam plate 96 advances past the hooks. As each hook 70 returns, the point 71 thereof pierces the curtain C and enters the groove 92, thereby securely pinning the curtain C to the rail as 10. The foot 100 of the shuttle 94 10 keeps the curtain C pressed against the member 76 while the hooks 70 are being retracted and restored. The foot 100 and cam plate 96 are adjustably attached to the shuttle 94, being carried respectively by a plate 102 and an arm 104, both 20 having slots therein through which a bolt 106 is passed, a wing nut 108 being threaded on the bolt 106. The arm 104 is shaped so that a portion of it extends parallel to the front face of the rail as 10 from the foot 100 to the cam plate 96, 25 bridging the groove 92 and passing beneath the retracted points 71 of hooks 70.

In attaching a curtain to the stretcher, a corner of the curtain is attached to a corner of the stretcher such as the junction between the rails 35 10 and 12, Fig. 1. This may be done either by manipulating the hooks at this corner of the stretcher or by providing a special finger (not shown) on the rail 10 or 12 for this purpose. An edge portion of the curtain C is held against the rail 10, and the shuttle 94 is pressed against the curtain and the rail while the cam plate 96 is moved in back of the first few hooks 70. The shuttle 94 then is moved along the rail 10, causing the hooks 70 to move outwardly past the edge 40 of the curtain C and then return into curtain engaging position. In this way the curtain is attached to the rail 10. In a similar manner another edge portion of the curtain is attached to the rail 12. The end bar 23 is slipped through the hem on the left side of the curtain, as viewed 45 in Fig. 1, and is held by the clamps 30 and 32 which are positioned on the rails 10 and 11 in accordance with the length of the curtain. The lower end of the bar 23 is slipped down between the fingers 62 and 64, Fig. 2, of the clamp 32 on rail 11, and the upper end of the bar 23 is hung on the tongue 44 of the clamp 30. The shuttle 94 then is employed to attach the lower edge of the curtain to the rail 11 in a similar manner. If 50 required, either or both of the rails 10 and 11 can be bent at their hinges 18 and 20 to facilitate attaching a shrunken curtain to the rail 11, the rails 10 and 11 being then straightened and held in such straight positions by the bar 22 and thumb screw 24. The curtain now is attached along all four edges thereof to the stretcher.

In removing the curtain from the stretcher, the shuttle 94 is employed again to effect retraction of the hooks 70. A slight pull on the curtain 55 70 as the hooks are retracted will suffice to withdraw the edge portion of the curtain for clearing the hooks 70 when they are returned to their normal portions. The shuttle 94 is moved along each of the rails 10, 11 and 12 in this manner for detaching the corresponding edges of the curtain

from these rails, and the bar 26 is slipped out of the curtain hem.

From the foregoing it will be appreciated that the above stated objects of the invention have been fulfilled. Thus, for instance, the former tedious and exacting operation of providing a plurality of holes in the rail to receive the pointed ends of the curtain hooks is eliminated by providing a novel rail construction having a single slot 92 that is easily and quickly formed in the rail to replace the row of holes heretofore regarded as necessary. It has been found that the curtain is held substantially as securely by the illustrated arrangement as it would be in the prior type of stretcher. The curtain fastening devices 68, instead of being disposed in individual slots which were formed by a time-consuming and relatively expensive operation upon the rail, are mounted on the rail simply by being clamped between a rail member as 76 and a strip as 78, Figs. 4 and 6. The novel formation of the fastening devices 68 enables them to be produced cheaply while insuring that they will be highly dependable in service. The shuttle 94 is of simpler construction than was heretofore deemed practicable, and its production cost is correspondingly lower. The arrangement including the adjustable end bar 23 for holding the curtain by its hem likewise is characterized by the advantages of simplicity and dependability. Furthermore, it enables the bar 26 to be clamped at any selected point on the rails 10 and 11 instead of at one of several arbitrarily pre-selected positions, the latter being a drawback of prior curtain stretchers wherein the end bar carried pins that fitted in holes afforded in the top and bottom rails.

While there has been illustrated and described a selected embodiment of the invention, it will be understood that various modifications may be made therein. Hence, I desire that the invention be construed to include all embodiments thereof coming within the spirit and scope of the appended claims.

The invention is hereby claimed as follows:

1. In a curtain stretcher, a rail including two longitudinally extending adjoining members, a row of resilient fastening devices having anchor portions disposed between said members, screws interconnecting said members, the anchor portions of said fastening devices being looped around said screws, and said fastening devices extending from the anchor portions thereof to lie normally against the face of said rail, pointed

hooks on the free ends of said fastening devices, said rail having a groove therein for receiving said hooks, and a shuttle slidable along said rail having a member adapted to cooperate with said fastening devices for moving said hooks out of said groove and then permitting said fastening devices to be restored for enabling said hooks to re-enter said groove.

2. In a curtain stretcher, the combination comprising a rail including two longitudinally extending separable members, curtain fastening devices, each comprising a wire of resilient material having an anchor portion clamped between said rail members, a coil spring adjacent said anchor portion, said wire extending from said coil spring and normally being urged thereby against a face of said rail, said rail having a first longitudinally extending groove therein disposed behind and transverse to the portions of said fastening devices adjacent said face, hooks on the ends of said fastening devices, said rail having a second groove therein to receive said hooks, a shuttle having a foot portion slidable along said rail, said second groove being intermediate said foot portion and said first groove, a cam plate carried by said shuttle adapted to travel in said first groove, and a supporting arm for said cam plate extending angularly from said foot portion and disposed across said second groove, said cam plate being effective first to move said hooks successively out of said second groove and then permit said hooks successively to re-enter said second groove as said shuttle is moved along the rail.

3. The combination set forth in claim 2, wherein said foot portion is unyieldingly attached to said shuttle and is adapted to press the curtain or like article against said rail as it is being attached thereto by said fastening devices.

KENNETH J. UNWIN.
